UNITED STATES PATENT OFFICE.

EMRI W. CLARK, OF NASHUA, NEW HAMPSHIRE.

DESIGN FOR A SNOW-GUARD FOR ROOFS.

SPECIFICATION forming part of Design No. 30,788, dated May 16, 1899.

Application filed April 12, 1899. Serial No. 712,812. Term of patent 14 years.

To all whom it may concern:

Be it known that I, EMRI W. CLARK, a citizen of the United States, residing at Nashua, county of Hillsborough, and State of New Hampshire, have invented and produced a new and original Design for Snow-Guards for Roofs; and I do declare the following to be a full, clear, and exact description of the same, reference being had to the accompanying drawings, forming a part thereof.

The herein-described design relates to what are known as "snow-guards," the same consisting of a thin body portion having a hook on one of its ends and a transversally-triangular guard attached to its other end.

Figure 1 represents a perspective view of my design. Fig. 2 is a side elevation of my design for a snow-guard.

In my design the leading features consist of the thin body portion *a*, having the hook portion *b* formed on one of its ends and the portion *c* bent at right angles to the face of

body portion *a* and extending longitudinally to the said body portion *a*. Attached to the bent portion *c* is the triangular guard portion *d* by means of the rivet *f*. Said guard portion *d* is provided with the wings *e e*, extending at right angles to its body portion. The base *g* of the triangular guard *d* is raised above the body portion *a*. Its apex *h* is rounded, as shown.

Having fully described my design, what I claim is—

The design for a snow-guard for roofs as herein shown and described. 35

In testimony whereof I have signed my name to this specification, in the presence of two subscribing witnesses, this 8th day of April, A. D. 1899.

EMRI W. CLARK.
